UNITED STATES PATENT OFFICE.

TOLEF O. BAKKEN, OF BODE, IOWA.

CHICKEN WATERER AND FEEDER.

Application filed April 26, 1923. Serial No. 634,700.

To all whom it may concern:

Be it known that I, TOLEF O. BAKKEN, a citizen of the United States of America, residing at Bode, in the county of Humboldt and State of Iowa, have invented certain new and useful Improvements in Chicken Waterers and Feeders, of which the following is a specification.

This invention relates to certain new and useful improvements in chicken waterers and feeders, and the primary object thereof is to provide a device of this character which enables the feed or water container while filled and connected to the trough, to be inverted or placed in operative position, without spilling or loss of the contents.

The primary object of the invention is to provide a device of this character, which is of simple and economical construction and which can be easily and quickly operated, and which at the same time is positive and certain in its operation.

The invention still further aims to provide a device of this type which embodies a minimum of parts and one wherein the parts are compactly assembled or related and which are not subject to easy derangement.

The invention has other and further objects, which will be later set forth and manifested in the course of the following description.

In the drawings:—

Figure 1, is a top plan view of the invention, the container being omitted;

Figure 2, is a section on line 2—2 of Figure 1, and

Figure 3, is a detail perspective view of the actuating device for sealing the container discharge mouth.

In proceeding in accordance with the present invention, a base is employed which may be stamped or pressed out of sheet metal and which involves an outer rim 1, bent inwardly and over to form an inner wall 2 and provided with a bottom 3, the latter disposed above the lower end of the outer rim or wall 1.

A ring or collar 4 is suitably secured at its lower end to the bottom 3, and forms a trough, of circular form, in conjunction with the bottom 3 and wall 2. The ring or collar 4 is formed with peripheral discharge openings 5 for the container contents. The upper end of the collar or ring 4 is turned over and threaded at 6 in order to threadedly receive the threaded neck 7 of a con-

tainer 8, the latter commonly styled or termed a "Mason fruit jar."

For the purpose of sealing the discharge mouth of the jar or container in order to prevent spilling of the contents, during inversion of the parts, a metal disk 9 is employed which slidably fits within the ring or collar 4 and against the edge of the mouth of the container. The under face of the disk 9 is engaged by an eccentric or cam 10, of the operating member, the latter being preferably formed of a section of wire and the eccentric being constituted of a curved part of the wire. One end 11 of the wire is extended through an opening provided therefor in the collar 4 and forms a journal, while the opposite end of the wire is likewise extended through a diametrically opposed opening in the collar 4 and is formed with an approximately right angular operating arm 12 having a handle 13, the latter located exteriorly of the collar.

In order to limit the downward movement of the sealing disk 9, a stop 14 is struck out from the collar 4.

In operation, the container is filled with feed or water and the base is threaded thereonto while the container occupies a vertical position, the handle 13 being operated to move the disk into sealing engagement with the discharge mouth of the container. The parts are now inverted and placed in the position of Figure 2, and since the disk 9 seals the container mouth, the contents of the container are prevented from egressing. The handle 13, is now manipulated to move the disk away from the container mouth thus permitting the container contents to flow through the openings 5 and into the trough.

The eccentric 10 moves to the left of Figure 2, consequently same supports one side of the disk, while the stop 14 supports the opposite side, when the disk is in inoperative position.

The handle 13, is formed and located so as to engage the upper edge of rim 1 to thereby limit pivotal movement of the eccentric in both directions.

What is claimed is:—

1. In a poultry feeder, a base having a rim and bottom, an interiorly threaded collar on the bottom spaced from the rim to form a trough in conjunction therewith and having discharge openings, a container threaded into engagement with the collar threads, a

- disk slidable in the collar for engagement with the container mouth to seal the latter, an operating member formed of wire having one end journaled in the collar and an intermediate part journaled in a diametrically opposite point in the collar, said wire having a curved part forming an eccentric engaging the disk and disposed between the said end and intermediate part thereof and having its opposite end formed with an operating handle, and a stop struck-out from the collar and engageable with the disk and located opposite to the direction of movement of the eccentric in the disk-releasing action of the latter.
2. In a poultry feeder, a base having a rim and an apertured collar forming a trough, a container threaded into engagement with the collar, a disk slidable in the collar for sealing the container mouth, an eccentric journaled in the rim and engaging the disk to releasably hold the latter engaged with the container mouth, and a stop carried by the collar and located opposite to the direction of movement of the eccentric in its disk-releasing action.
3. In a poultry feeder, a base having a trough, a container, means to connect the container to the base, a disk for closing the mouth of the container, an eccentric pivoted to the base and engageable with the disk for moving the latter into and out of operative position, and means to operate the eccentric having a part engageable with the base to limit the swinging movement of the eccentric in both directions.
4. In a poultry feeder, a base having a bottom and a vertical wall, an apertured collar secured to the bottom and located within the wall to form a trough in conjunction with the bottom and vertical wall of the base, an eccentric within the collar and pivoted thereto, a disk for closing the container mouth engageable with the eccentric to be moved by the latter into and out of engagement with the container mouth, and an arm on the eccentric to operate the same and formed to engage with the vertical wall to limit the swinging movement of the eccentric in both directions.
5. In a poultry feeder, a trough, an inverted container, means to releasably secure the filling and discharging mouth of the container to the trough, means to seal the mouth, and manually operated means independent of and disposed exteriorly of the container to releasably hold the sealing means in engagement with the mouth or out of engagement therewith.
6. In a poultry feeder, a trough, an inverted container, means to releasably secure the filling and discharging mouth of the container to the trough, means to seal the mouth, means to releasably hold the sealing means in engagement with the mouth, and manually operated operating means for the holding means carried by and engageable with the trough to limit movement of the holding means to both operative and inoperative positions thereof and to positively hold same in either of said positions.
7. In a poultry feeder, a trough, a container releasably connected to the trough and having a discharge mouth, means to close the mouth, and manually operated means carried by the trough to operate the mouth closing means and to positively hold same in either open or closed position.
8. In a poultry feeder, a trough, a container releasably connected to the trough and having a discharge mouth, means to close the mouth, and manually operated means carried by the trough and engaging with and beneath the mouth closing means to operate the latter and to positively hold same in either open or closed position.

In testimony whereof I affix my signature.
TOLLEF O. BAKKEN.
